Primary Examiner — Kevin K Rudzinski*Assistant Examiner* — Clare Ann Gannon(74) *Attorney, Agent, or Firm* — Dunlap Bennett & Ludwig, PLLC; Brendan E. Squire(57) **CLAIM**

The ornamental design for a massage mat, as shown and described.

DESCRIPTION

FIG. 1 is a top front perspective view of a massage mat; FIG. 2 is a top elevation view thereof; FIG. 3 is a front elevation view thereof, the rear elevation view being a mirror image thereof; FIG. 4 is a right elevation view thereof, the left elevation view being a mirror image thereof; and, FIG. 5 is a bottom elevation view thereof. The broken lines shown in the drawings depict portions of the massage mat that form no part of the claimed invention.
